Attorney

UNITED STATES PATENT OFFICE.

ALEWELLYN T. SAVAGE, OF BOSTON, MASSACHUSETTS, ASSIGNOR TO JOHN M. KEYES AND LAURA H. KEYES, BOTH OF CONCORD, MASSACHUSETTS.

OUTBOARD-ENGINE BRACKET.

Application filed April 18, 1928. Serial No. 270,871.

My present invention relates to brackets for outboard engines, and is a modification of the structures illustrated, described and claimed in my prior and copending applications, Ser. No. 183,495, filed Apr. 13, 1927, and Ser. No. 249,269, filed January 25, 1928, as well as being an improvement over said structures.

An important object of the present invention is the provision of an outboard engine bracket which is inexpensive to manufacture, light in weight, and of a size to be conveniently stored when not in use.

In my said prior and copending applications, I have illustrated two types of outboard engine brackets having adjustable and pivoted arms, of varying length, and with pivoted tongues on their outer ends to fit in sockets attached to the external hull of a boat or vessel. Under the present building programs for boats, however, there is a tendency toward standardization of construction, so that a great many boats of one size, shape, design, style and contour will be produced. Another object of the present invention, therefore, is to provide a bracket which likewise will be standardized as to construction, in such manner that adjustability of arms and pivoting of the tongues will not be necessary, the length of the arms, and the pitch or angle of the tongues being predetermined for a given class of boats or vessels, and the entire outboard engine bracket being then cast as a unit. It will be instantly apparent that this results in a great saving in manufacturing expense, as well as eliminating the time heretofore required in assembling these brackets. The bracket produced as above briefly outlined is rigid, strong, compact, and is possessed of many of the advantageous features of the brackets described in said copending applications, viz, such as the safety factor of ten to one, a feature whose value will be instantly understood and appreciated by those skilled in this art.

A further advantageous feature which is present in this bracket construction is the deflection of the exhaust gases, soot, and the like from direct contact with the boat or vessel on which the engine is utilized. This is an important consideration, since, when utilizing an outboard engine or motor on a boat with white or light paint, the finish becomes quickly soiled, marring the appear-

ance of the boat, unless my novel outboard engine brackets are utilized.

When the bracket is attached to the side of a vessel, the outboard engine attached thereto may be swung on its own pivot, by 60 means of its tiller or tiller ropes, in order to properly position the engine for efficient forward propulsion of the vessel.

In the present bracket, I may also utilize the arcuate bottom edge of the bracket, permitting attachment to boats having rounded sterns, which is a decided advantage.

The above and other objects of the invention, features, details of construction, advantages and combinations, will be herein-after more fully pointed out and claimed.

Referring to the drawings, illustrating a preferred embodiment of my present invention,

Fig. 1 is a plan view of the quarters and stern of a boat with my novel brackets attached at a plurality of points;

Fig. 2 is a cross-sectional view illustrating the integral tongue and arm, and socket construction, and method of application to a 80 hull;

Fig. 3 is a vertical sectional view of the bracket in position, illustrating the method of attaching the outboard engine clamps thereon; and

Fig. 4 is a perspective view, on an enlarged scale, of the bracket.

Referring now to the drawings for a particular description of the invention, and its method of application and operation, 1 designates a vessel or boat, the quarters and stern only showing, and at A and B are illustrated two positions for my device. At A the bracket and an outboard engine are mounted at the stern of the boat, and at B they are mounted at the side. If desired another engine and bracket may be mounted on the port side as well as on the starboard side, or the engine could be mounted on the sides only and not the stern, or at the stern alone.

The present invention comprises a plurality of socket members 2 affixed to the boat 1 by lag screws 3 or the like. These sockets are preferably partially imbedded in the hull, as illustrated, for great strength, neatness of appearance, and permanence. A plate 5 is provided, preferably constructed of metal, the same being provided with a plurality of spaces 6, for 110

lightness of weight, although a solid plate may be utilized if desired. Positioned in two of the apertures 6, and adjacent to the top of the plate, are a pair of blocks 7, 7, 5 against which the locking screws 8 of the engine clamps 9 are adapted to grip. The apertures in which the blocks 7 are fitted may be formed as recesses, with closed backs if desired, for greater strength. 10 These blocks are preferably of hard wood, rather than metal, to afford a better biting and gripping surface than metal, and are of course removable and replaceable when worn, screws 20 being provided to retain them in place.

15 Integral with the plate 5, and substantially midway of the top thereof, is a rigid arm 11, and on its free end this arm has an integral tongue 12. This tongue 12 is 20 adapted to slide into and engage the upper socket member 2, and will be held therein by the weight of the bracket and the engine attached thereto. These socket members 2 are preferably arranged in a triangular position 25 on the hull, a single socket member 2 being provided for the tongue 12, and two sockets being arranged below this upper socket 2, to receive the tongues 13, formed integral with the arms 15, which arms are 30 in turn formed integral with the plate 5.

Thus the entire plate 5, arm 11 and tongue 12, arms 15 and tongues 13, can be cast in a unit, the arm 11 being cast in a predetermined angle to the plate 5, and the 35 tongues 13 being cast in a predetermined angle to the arms 15. The simplicity of this structure will instantly appeal to those skilled in this art.

The bottom of the plate 5 is formed arcuate, as illustrated at 14. The arms 15 being shorter than the arm 11, the bottom of the plate 5 will be inclined toward the hull of the boat at a predetermined fixed angle, and due to the rounded or arcuate formation 40 of the bottom of the plate, the same is adaptable to boats having rounded sterns, a feature which is important, as it has not been possible, so far as I am aware, to heretofore apply an outboard engine to a rounded stern in a practicable manner.

50 Also, in view of the standardized construction of boat hulls, the angle of the arms 15 and arm 11 relatively to the plate 5, as well as the angle of the tongues 13 and 12 relatively to the arms 15 and 11, can be predetermined, and cast in this predetermined form, an extremely important feature of saving and economy of manufacture.

60 I have discovered that, by my present novel method of applying the brackets, viz, with a single tongue and socket at the top and a pair of tongues and sockets at the lower portion of the bracket, a safety factor 65 of approximately ten to one is obtained,

thus insuring against any damage or injury otherwise due to the thrust of the engine.

It will thus be apparent that I have devised a novel outboard engine bracket, possessed of numerous advantage and efficiency. This bracket is readily attachable and detachable, and when the engines and brackets are removed, they may be stowed on board the boat in a small space, which is an advantage not enjoyed when a fixed power plant is utilized on the interior of the boat. Also the odors, danger and numerous disadvantages incident to fixed power plants within the boat are eliminated, and thus the safety factor of my present 75 device is greatly increased, and will be appreciated by boat owners and yachtsmen in general.

Also, when detached and the boat used simply for a sailing craft, the drag incidental to fixed propellers is eliminated, another feature of interest and value.

In Fig. 1 at B, the engine 17 is illustrated attached to the bracket, and turned on its own pivot, by means of its tiller 18, in a direction to afford greatest propulsion to the boat 1, viz, at right angles to the bracket.

At A, Fig. 1, the engine 19 is affixed to the bracket and is illustrated as driving straight ahead. It will be appreciated that tiller 95 ropes may be utilized instead of the tillers illustrated, thus rendering control of the outboard engines easier, particularly when the boat has a high freeboard and the bracket is set considerably below the rail.

100 While I have necessarily illustrated and described my present invention somewhat in detail, it will be appreciated that I may vary the size, shape and arrangement of parts within reasonably wide limits without departing from the spirit of the invention.

105 My invention is further described and defined in the form of claims as follows:

1. An outboard engine bracket, comprising a plate, a plurality of arms of varying length integral with said plate, tongues on the ends of said arms, and sockets adapted to be affixed to the hull of a boat to receive said tongues.

110 2. An outboard engine bracket, comprising a plate, a plurality of arms of varying length integral with said plate, tongues integral with the ends of said arms, and sockets adapted to be affixed to the hull of a boat to receive said tongues.

115 3. An outboard engine bracket, comprising a plate, a plurality of arms of varying length integral with said plate and set at a predetermined angle to said plate, tongues on the ends of said arms, and sockets adapted to be affixed to the hull of a boat to receive said tongues.

120 4. An outboard engine bracket, comprising a plate, a plurality of arms of varying length integral with said plate and set at a 125

predetermined angle to said plate, tongues integral with the ends of said arms, and sockets adapted to be affixed to the hull of a boat to receive said tongues.

5. An outboard engine bracket, comprising a plate, a plurality of arms of varying length integral with said plate and set at a predetermined angle to said plate, tongues integral with the ends of said arms and set at a predetermined angle to said arms, and sockets adapted to be affixed to the hull of a boat to receive said tongues.
- 10 6. An outboard engine bracket, comprising

ing a plate having an arcuate bottom edge, a plurality of arms of varying length integral with said plate, the arms adjacent to said arcuate bottom edge being shorter than the arms elsewhere on said plate, said arms being set at a predetermined angle to said plate, tongues integral with the ends of said arms and set at a predetermined angle to said arms, and sockets adapted to be affixed to the hull of a boat to receive said tongues.

In testimony whereof, I have signed my name to this specification.

LLEWELLYN T. SAVAGE.
